UNITED STATES PATENT OFFICE.

LEONARD R. STEEL, OF CLEVELAND, OHIO.

WATER-COOLER.

1,004,927.

Specification of Letters Patent.

Patented Oct. 3, 1911.

Application filed October 7, 1910. Serial No. 585,825.

To all whom it may concern:

Be it known that I, LEONARD R. STEEL, a citizen of the United States of America, residing at Cleveland, in the county of Cuyahoga and State of Ohio, have invented new and useful Improvements in Water-Coolers, of which the following is a specification.

This invention relates to improvements in water coolers and more particularly to the type wherein a bottle or similar receptacle is placed in an inverted position on a suitable support so that water may be drawn therefrom. It is common practice with most devices of this kind to insert the neck of the bottle into a cup or chamber from which extends a faucet. The cup or chamber is usually arranged in an ice chest and is considerably less in diameter than the ice chest so that the intervening space may be filled with ice to maintain the water within the chamber in a cool state. It is obvious with this construction that the ice has little or no effect on the water within the bottle since the water must of necessity pass from the bottle into the chamber and there remain for a period in order to be chilled by the ice. It has been found with the use of devices of this kind that when water is taken at frequent intervals from the cooler it is never thoroughly chilled, due to the comparatively short time it remains in the cup or chamber before passing through the faucet. The present invention therefore aims to remedy this defect by providing a specific form of bottle internally provided with an ice chamber so positioned that the entire volume of water in the bottle will be acted upon by the ice and maintained in a cool state.

An object of the invention is the provision of a jacket or casing for the bottle, the said jacket or casing being provided with suitable insulation to protect the contents of the ice chamber from the atmospheric temperature so that the ice within the chamber may be preserved for an indefinitely long period.

With these and other objects in view, which will more fully hereinafter appear, the present invention consists in certain novel details of construction and arrangement of parts, hereinafter fully described, illustrated in the accompanying drawings, and more particularly pointed out in the appended claim; it being understood that

various changes in the form, proportion, size, and minor details of the device may be made, within the scope of the appended claim, without departing from the spirit or sacrificing any of the advantages of the invention.

In the accompanying drawings, forming part of the specification: Figure 1 is a side elevation of the device with the upper end portion thereof shown in section. Fig. 2 is a similar view with the lower end portion shown in section.

Similar numerals of reference are employed to designate corresponding parts throughout.

The jacket is preferably formed of metal and comprises an outer casing and an inner casing. The outer casing comprises a cylindrical body portion designated by the numeral 5 and is provided at one end with a bottom 6. The inner casing is designated by the numeral 7 and at one end is provided with a bottom 8. The bottoms 6 and 8 are centrally provided with alining circular openings and a circular wall 9 is secured to the edges of these openings by means of solder or the like in order to insure a tight joint. A rabbet 10 is formed on the inner surface and at the upper end portion of the inner casing 7, the upper edges of the outer and inner casings being connected and held in spaced relation by means of an angle strip 11. The space between the outer and inner casings is filled with cork, asbestos or other suitable heat insulating material as shown at 12. The cover for the jacket is shown to include a circular body portion designated by the numeral 13 from the peripheral portion of which depends a flange 14. The flange 14 is, adjacent to its lower end and on its outer surface, undercut as shown at 15 and received by the rabbet portion 10. As shown in the drawings the top or cover comprises outer and inner casings held in spaced relation, the space therebetween being filled with cork, asbestos or other suitable heat insulating material as shown at 16.

The bottle is shown to include a cylindrical body portion designated by the numeral 17. In the following description of the several parts of the bottle it is assumed that the bottle is in an upright position and not inverted as shown in the drawings. The body portion 17 is provided at one end with a bottom 18, and at its opposite end is pro-

vided with an end wall 19 having a central opening from which rises a neck 20. The bottom 18 is formed with a central opening from which rises a cylindrical chamber 21, the upper end of which is closed by an end wall as shown at 22 and extends to a point adjacent to the neck 20. A cap or closure comprises a circular body portion 23 somewhat greater in area than the area of the opening in the bottom 18, and depending from the lower face of the peripheral portion of the body 23 is a flange 24, of a size to nicely fit within the opening of the bottom 18. Removably secured in the chamber 21 is a hollow cylindrical metallic casing 24', closed at one end as shown at 25.

Fixedly secured to the outer surface of the neck 20 and corresponding in width to the length of the latter is an exteriorly 20 screw-threaded metallic band 26. An interiorly screw-threaded sleeve is designated by the numeral 27 and is adapted to be screwed onto the band 26. The sleeve 27 is considerably greater in length than the 25 length of the neck or band, and the end portion of the sleeve extending beyond the neck and band is reduced in diameter as shown at 28 and interiorly screw-threaded for the reception of a faucet 29.

30 In the operation of the device and before the faucet is connected with the sleeve the bottle is filled with liquid through the opening of the neck. The jacket is now placed over the bottle so that the neck thereof will 35 extend through the opening in the bottom

of the jacket. This done the faucet 29 is screwed into the sleeve and the device inverted and placed upon a suitable support, after which the casing in the chamber 21 is filled with ice and covered and the cover 40 placed upon the jacket.

From the foregoing it is evident that I have provided a device which is comparatively simple in structure and inexpensive to manufacture, embodying few parts and 45 those so arranged that the danger of derangement will be reduced to a minimum.

I claim:—

A water cooler comprising a jacket having heat insulating walls and an apertured 50 bottom, a liquid receptacle mounted in the jacket and provided with an end portion wholly resting upon the bottom of the jacket and provided with a liquid discharge portion disposed in the aperture in the bottom 55 of said jacket, the said liquid receptacle having its upper end extended above the plane of the open end of the jacket, and a closure extending over the upper end of the liquid receptacle and provided with a depending 60 flange disposed in the same general plane with the vertical walls of the jacket and detachably fitting the same at the open end of said jacket.

In testimony whereof I affix my signature 65 in presence of two witnesses.

LEONARD R. STEEL.
